(57) CLAIM

The ornamental design for a chiropractic massage tool, as shown and described.

DESCRIPTION

FIG. 1 is a front elevational view of a chiropractic massage tool, showing my new design;

FIG. 2 is a left side elevational view which is a mirror image of the right side view;

FIG. 3 is a rear elevational view;

FIG. 4 is a bottom plan view;

FIG. 5 is a top plan view;

FIG. 6 is a front perspective view; and,

FIG. 7 is an environmental view of the tool in use.

The broken line drawings of patient and doctor are for illustrative purposes only and form no part of the claimed design.
